UNITED STATES PATENT OFFICE.

JAMES T. LIVERS, OF EVANSVILLE, INDIANA, ASSIGNOR TO THE GRAHAM GLASS COMPANY, OF EVANSVILLE, INDIANA, A CORPORATION OF INDIANA.

DESIGN FOR A BOTTLE.

Application filed February 15, 1926. Serial No. 16,534. Term of patent 14 years.

To all whom it may concern:

Be it known that I, JAMES T. LIVERS, a citizen of the United States, residing at Evansville, county of Vanderburg, State of Indiana, have invented a new, original, and ornamental Design for Bottles, of which the following is a specification, reference being had to the accompanying drawing, forming a part thereof.

Figure 1 is a front elevation of the bottle embodying my design.

Figure 2 is a side elevation of the same.

Figure 3 is a transverse section of the same taken on the line 3—3 of Figure 1.

I claim:

The ornamental design for a bottle, as shown.

JAMES T. LIVERS.
